DOUBLE-ACTION DOOR HOLDER

Harper E. Dunlap, Walled Lake, Mich.

Application July 26, 1950, Serial No. 175,940

2 Claims. (Cl. 16—65)

1

This invention relates to door holders.

One object of this invention is to provide a double-action door holder which, when the door is nearing its closed position, will urge the door into its closed position but which, when the door is nearing its open position, will also urge the door into its open position.

Another object is to provide a door holder of the foregoing character which is of simple and inexpensive construction and which preferably employs a single spring for both the outward and inward door-urging actions.

Another object is to provide a double-action door holder of the foregoing character which has a swinging rod which also slides through a pivot member, such as a screw eye, and swings over a dead center position on one side of which it urges the door closed and on the other side thereof urges the door open.

In the drawing:

Figure 1 is a top plan view, partly in horizontal section, of a double-action door holder according to one form of the invention, in the closed position of the door and taken along the line 1—1 in Figure 3;

Figure 2 is a view similar to Figure 1, but showing the position of the door holder in the open position of the door;

Figure 3 is a vertical section taken along the line 3—3 in Figure 1; and

Figure 4 is a top plan view of the spring used in the double-action door holder of Figures 1 to 3 inclusive, shown in its relaxed position removed from the door holder.

Referring to the drawing in detail, Figures 1 to 3 inclusive show a double-action door holder, generally designated 10, as applied to a door or other closure 11 which is hinged as at 12 to a door frame or door opening structure 13 so as to urge the door 10 either into the closed position of Figure 1 or into the open position of Figure 2. The door 11 has been illustrated as swinging outwardly in a horizontal direction from a door frame 13, but it will be understood that the door 11 may consist of any suitable closure, such as a box lid, cabinet or cupboard door or the like.

The door holder 10 consists of a screw eye 14 which is threaded as at 15 into the door 11 a short distance from the axis of the hinge pin 16 of the hinge 12. A second screw eye 17 is threaded upwardly as at 18 into the lintel 19 of the door frame 13 (Figure 3). A push rod 20 is passed through the screw eye 17 and has an approximately S-shaped bent end portion 21 passing through the eye of the screw eye 14 and

15 having a hooked end portion 22 projecting beyond the screw eye 14 and serving as an anchorage for the ring-shaped end 23 of a helical-tension spring 24, the opposite ring-shaped end 25 being anchored in a slot 26 in the end of the push rod 20 opposite the S-shaped end portion 21. The helical spring 24 is divided into forward and rearward portions 27 and 28 respectively by a gap 29 across which one of the convolutions 30 of the spring 24 passes (Figure 4). The gap 29 is preferably formed in the spring during its manufacture. This gap 29 is very slight and may be formed by stretching the spring at this point beyond its elastic limit before heat-treating.

The spring 24 is considerably shorter than the rod 20 so that it is in a tensioned condition when mounted, as shown by the contrasting appearances of Figures 1, 2 and 4. The bent portion 21 of the push rod 20, in addition to the hook portion 22, has a shallow U-shaped portion 31 which extends around one side of the screw eye 14 (Figure 3) to align eye 42 with rod 20.

In the installation of the double-action door holder of the present invention, the operator first installs the screw eye 17 at a sufficient distance from the side of the door frame 13 and slightly inward from its edge. The gap 29 of the spring 24 is then placed into coincidence with the screw eye 17 by pushing the spring 24 relatively to the screw eye to make the screw eye enter the gap 29. The forked end 26 of the push rod 20 is then passed entirely through the spring 24 from one end to the other and also through the screw eye 17, and the ring portion 25 of the spring 24 hooked into the slot 26 in the push rod 20, tensioning the spring portion 28 of the spring 24. The screw eye 14 is then mounted in the door on substantially the same level as the screw eye 17 slightly inward from the inner edge of the door. The door screw eye 14 is then held in a vertical position while the bent end 21 of the push rod 20 is inserted through this screw eye, after which the screw eye 14 is turned into a horizontal position to lock the bent end 21 in position. The operator then hooks the ring portion 23 of the spring 24 over the hook portion 22 on the S-shaped bent end 21 of the push rod 20, tensioning the spring portion 27.

In the operation of the invention, let it be assumed that the double-action door holder 10 has been installed in the manner described above and that the door or other closure 11 has been closed (Figure 1). In this position, the spring portions 27 and 28 exert pulls upon the opposite ends of

the push rod 20 toward the screw eye 17 where the spring 24 is anchored by the connecting portion or convolution 30. Since the spring portion 28 is stretched out much farther than the spring portion 27 in this position of the door 11, the spring portion 28 will exert the greater pull, hence will overbalance the opposite pull of the spring portion 27 and as a result will push the push rod 20 toward the left, forcing its bent end 21 to push against the screw eye 14 and hold the door 10 closed.

If, on the other hand, the operator now pulls the door open, and in so doing swings the push rod 20 over a line A—D—B interconnecting the axis of the hinge pin 16 and the axis of the shank of the screw eye 14, the spring portion 27 will become more greatly tensioned and the spring portion 28 somewhat less tensioned. Under these circumstances, the spring portions 27 and 28 will exert equal pulls in opposite directions, counteracting one another and hence holding the door 11 in its open position. The point D located intermediate the screw eye 17 and the hinge pin 16 is in the same radius from the axis of the hinge pin 16 as the point of contact of the bent rod end 21 with the screw eye 14 from the hinge pin 16, and is therefore the dead center position. When the door is swung inward from the Figure 2 position toward the line A—B, so long as it remains on the outer side of the line A—B it will spring outward when released. If, however, this contact point passes over the line A—B, and hence over the dead center point D, the spring portion 28 overbalances the spring portion 27 and the door is pulled into its closed position. It will be obvious that this contact point in the closed position of the door, must be inside the line A—B.

It will be seen that the door can be pulled outward beyond its position of equilibrium in Figure 2 without damage to the door. Moreover, the door will always open with an even pull, in contrast to friction catches or detents, which results in a different pull being necessary to open different doors. In other words, the retarding effect of a friction catch or detent is variable, whereas the action of the present door holder is substantially constant for door holders with the same construction and employing similar springs 24. Finally, the present door holder is substantially independent of gravity so that when a door is hung out of plumb, for example, gravity will not close or open it.

While the invention has been illustrated and described as applied to a wood door mounted in a wood door frame, it will be obvious that it may

equally well be applied to a metallic door merely by substituting a base or mounting plate which carries either screw eye and is secured to the door or door frame, as the case may be. The invention may be applied to vertically-swinging doors, such as garage doors, as well as to horizontally swinging doors. Thus, the invention protects both the door and its hinges and the door holder from damage by swinging the door or other closure too widely open.

What I claim is:

1. A double-action door holder for attachment between a door frame and a door, comprising an eye member attachable to the door, a second eye member attachable to the door frame, a push rod pivotally engaging one of said eye members and slidably engaging the other eye member, and a tension spring having its opposite ends secured to the opposite ends of said rod and having an intermediate portion thereof secured to said door frame eye member, said rod passing substantially through the center of said spring and substantially along the axis thereof, said spring having a pair of spaced tension portions with a gap therebetween adapted to receive said door frame eye member.

2. A double-action door holder for attachment between a door frame and a door, comprising an eye member attachable to the door, a second eye member attachable to the door frame, a push rod having a bent end portion pivotally engaging one of said eye members and slidably engaging the other eye member, and a tension spring having its opposite ends secured to the opposite ends of said rod and having an intermediate portion thereof secured to said door frame eye member, said rod passing substantially through the center of said spring and substantially along the axis thereof, said bent end portion having a hook portion thereon adapted to receive one of said opposite ends of said spring, said rod having a slotted end portion adapted to receive one of said opposite ends of said spring, said spring having a pair of spaced tension portions with a gap therebetween adapted to receive said door frame eye member.
